KNOCKDOWN CHEST

Filed Feb. 7, 1946

UNITED STATES PATENT OFFICE

2,539,658

KNOCKDOWN CHEST

Harry Derman, Great Neck, N. Y.

Application February 7, 1946, Serial No. 646,112

10 Claims. (Cl. 229—23)

1
 This invention relates to what is commonly referred to as a chest of the knockdown or collapsible type. More particularly, the invention deals with articles of manufacture of the class defined, wherein the chest comprises three primary parts, two of which are similar end wall sections and the third comprising a body and cover wall section. Still more particularly, the invention deals with devices of this type and kind formed from sheets of paper, corrugated board or similar material pre-shaped and assembled in each of the sections and constructed to provide reinforced portions as and where required, so as to enable the chest to withstand heavy loads and, further, to form a seat or bench capable of holding one hundred pounds or more.

The novel features of the invention will be best understood from the following description, when taken together with the accompanying drawing, in which certain embodiments of the invention are disclosed and, in which, the separate parts are designated by suitable reference characters in each of the views and in which:

Fig. 1 is a perspective view of an assembled chest made according to my invention.

Fig. 2 is a section on the line 2—2 of Fig. 1 on an enlarged scale.

Fig. 3 is a section on the line 3—3 of Fig. 1 on an enlarged scale.

Fig. 4 is a bottom plan view of one end portion of the chest with parts of the construction broken away and in section.

Fig. 5 is a plan view of the blank from which the end wall portions are formed.

Fig. 6 is a perspective view of the sheet from which the main body walls of the chest are formed in a partially assembled position.

Fig. 7 is a perspective view of a top cover wall reinforcement with part of the reinforcement in section and with part shown in extended position in dot and dash lines; and

Fig. 8 is an enlarged detail view of the upper end of one post showing the mounting of the chest walls thereon.

Chests of the type and kind under consideration are adapted for use in storage of articles of various types and kinds and may be practically used in the storage of playthings for children and used in a playroom. Chests of the kind under consideration have been of rather weak or flimsy construction and, as and when children have sat upon the chests, it has often been experienced that the chests have collapsed due to the weakness thereof.

It is one of the distinctive features of my invention to so reinforce the entire chest structure as to enable the chest to not only support playthings or other articles, but also be sufficiently sturdy to withstand the weight of one or two children, so that the chest can be conveniently

used as a seat or bench for the children in a playroom.

The chest is constructed from two units or sections, namely a body section 10 and end wall section 11, two of the latter being employed in forming end walls of the chest and, for purposes of designation, the unit or section to the right of Fig. 1 will be identified as 11 and the unit or section to the left, identified as 11'; as both of these sections or units are identical, the brief description of one will apply to both.

The body section or unit 10 is formed from an oblong rectangular sheet of suitable material folded to form the front wall portion 12, the bottom wall 13, back wall 14, and top or cover wall 15.

The bottom wall 13 is a trifle longer than the other walls and has its corner portions cutout, as seen at 16, to form at the ends of the bottom wall 13 projecting members 17 adapted to seat upon the end wall sections, as later described.

The upper edge of the front wall 12 has an integral foldable reinforcing and stop member 18 comprising a narrow top wall portion 19 and two wall portions 20, 21, to form of the resulting member 18, note Fig. 2, a V-shaped reinforced upper edge along the front wall of the chest to form a strong stop and support for the top or cover 15.

The top or cover 15 comprises the single sheet, as shown in Fig. 6, to which is secured a reinforcing member 22 which comprises an elongated sheet composed of two wall parts 23 and 24 foldably united, as at 25, the parts 23 and 24 being substantially of the same general peripheral dimensions. Each of these parts have inturned side flanges, as at 26 and 27, respectively, to form a finish at the ends of the resulting cover 15. Foldable with the free edge of the part 24, as at 28, is a supplemental part 29 which is shown in extended position in dot and dash lines in Fig. 7 and collapsed upon the inner surface of the part 24 in full lines. The part 29 is of less length than the part 24 and fits within the flanges 27 so as to lie flush with said flanges. The sheet forming the top wall 15, as in Fig. 6, fits within the flanges 26 and, for purposes of identification, this wall part is designated in Fig. 3 of the drawing as 15', whereas the entire top wall, including the assemblage of the member 22 on 15', will be designated by the reference character 15.

In assemblage, the part 29 is glued or otherwise secured to the part 24 and the part 15', including the flanges 26 and 27, are glued to the respective parts and to each other, so as to form a complete top wall portion of four ply thickness as will appear from a consideration of Figs. 2 and 3 of the drawing. It will be understood that the flanges 26 and 27, including adjacent portions of the parts 23 and 24, form extensions on the top

or cover wall at the ends of the resulting chest, as clearly seen in Figs. 3 and 4 at the front edge 39 of the cover 15 also projects slightly beyond the front wall of the cover to form a flange portion facilitating movement of the cover into open position.

Each end wall section 11, 11' is formed from a sheet similar to the blank 31, shown in Fig. 5 of the drawing, and two corner posts and leg members 32, 32'.

The blank sheet 31 comprises a large rectangular central wall part 33, at the ends of which are two narrow parts 34 and 35 foldable with respect to the part 33 on the lines 36 and 37. Beyond the part 34 are two foldable parts 38 and 39 and, beyond the part 35, are two foldable parts 40 and 41. The narrow part 35 has its ends notched, as seen at 42; whereas the parts 38 and 39 are narrower than the part 33 and join the part 33 in bevelled wall flaps 43 at the ends of the part 34. The flaps 43 seat upon the upper ends of the post or leg members 32, 32' and, assuming that the posts 32 are regarded as the front posts or leg members; on these posts are also adapted to seat similar flaps 44, formed at the ends of the part 18, in the manner illustrated in Fig. 8 of the drawing. As both posts 32, 32' are of the same construction, the brief description of one will apply to the other. Each of these posts is rectangular in cross-sectional form and have on two surfaces thereof longitudinal grooves, as at 45 and 46. These grooves extend the full length of the posts or leg members 32, 32' and the grooves 45 are adapted to receive the end edges of the wall 12 in one instance and corresponding edges of the wall 14 in the other instance; whereas the grooves 46 are adapted to receive the side edges of the wall part 33. The wall parts 33 are pre-coupled with the posts or leg members 42, 42' by large headed nails or other fasteners 47, whereas similar fasteners 47' are utilized in detachably coupling the end sections or frames 11-11' of the chest with the body section 10. In this connection, it is preferred that the posts 32, 32' be pre-drilled with holes to receive the fasteners 47, so that these fasteners may be properly positioned and, further, to simplify the assemblage in setting up the chest for use. The parts 38 and 39, which are at the upper ends of the wall parts 33, are folded downwardly and, then, upwardly upon inner surfaces of the wall parts 33 and are secured thereto by staples or other devices, as at 48, to form reinforcing members 49 at the upper ends of the wall 33 intermediate the posts 32, 32' and similar to the members 18, so that along the front and side walls of the resulting chest strong supports are provided for the top or cover 15. It will be noted from a consideration of Fig. 4 of the drawing that the member 18 is also secured to the front wall 12 by staples or other devices 50, similar to the devices 48, the devices 50 being spaced longitudinally of the front wall and two or three thereof will be sufficient to hold the member 18 in position.

The notched-out portions 42 of the part 35 are adapted to receive the corner portions of the posts as the part 35 is extended inwardly at right angles to the wall 33 to form a stop or ledge for supporting the projecting ends 17 of the bottom wall 13, as clearly seen in Fig. 3 of the drawing. This latter support is further reinforced by the parts 40, 41 which are folded upon themselves and are both at right angles to the part 34; the folded parts 40, 41 have end portions 51 which overlie

the inner surfaces of the posts 32, 32' and are secured thereto by headed nails or other fasteners 52, note Fig. 2 of the drawing. The parts 35, 43 and 41 materially reinforce and strengthen the end walls and form additional braces and supports for the end walls and a means for directly taking up the load upon the bottom wall 13 of the chest, as will be apparent. The parts 40, 41 collectively are of a length equal to the 10 downwardly extending leg ends of the posts 32, 32'. The resulting construction forms a bottom wall in the chest which is raised above the floor or other supporting surface as will clearly appear from a consideration of Figs. 1, 2 and 3 and the 15 parts 40, 41 also form closures at the ends of the chest.

In production of knockdown chests of the kind under consideration, the main body part 10, including the member 22 glued or otherwise permanently attached to the wall part 15', constitutes one part or section of the chest structure and the other two parts comprise the assembled end sections 11, 11' and by "assemblage" is meant the wall part 33 assembled in the post or leg members 32, 32'. It will thus be apparent that the wall parts of the section 10, in a flat condition or relationship with the sections 11, 11' arranged thereon, will form a relatively thin package, the end sections laid end to end being preferably of a length equal to the length of the top wall 15. The resulting package would be of a length equal to the length of the top wall part 15 and of a combined thickness of the folded walls with the end sections 11, 11' thereon. This compact packaging facilitates storage, as well as shipment and handling of the chest and the purchaser can quickly and easily make the complete assemblage by simply placing the end edges of the walls 12 and 14 in the grooves 45 and with the extensions 17 upon the supports 35 and, then, by placing the nails or fasteners 47' in position, being certain to hold the end sections, one at a time, in snug engagement with the ends of the walls 12 and 14. It will also be apparent that the flaps 43 and 44, fitting upon the upper ends of the posts, also aid in the support of articles placed in the chest and, at the same time, form a neat and finished surface and a relatively wide flat cover support for the cover 15, the hinge of which is formed by the fold, as at 53.

Having fully described my invention, what I claim as new and desire to secure by Letters Patent is:

1. A knockdown chest comprising a body section and two similar end wall sections, said body section comprising foldably related front, back, bottom and top wall parts, said end sections each comprising a pair of corner posts joined and spaced solely by a wall portion, said wall portion having, at upper and lower ends thereof, inwardly extending reinforcing members formed integral therewith, the front wall of the body section having, at its upper edge, an integral reinforcing member, said member, in combination with the upper reinforcing members of the end wall sections, forming a support for the top or cover part of the resulting chest, the corner posts extending below the bottom wall of the assembled chest and said bottom wall having end extensions seating upon the inwardly extending bottom reinforcements of said end walls.

2. A knockdown chest comprising a body section and two similar end wall sections, said body section comprising foldably related front, back,

bottom and top wall parts, said end sections each comprising a pair of corner posts joined and spaced solely by a wall portion, said wall portion having, at upper and lower ends thereof, inwardly extending reinforcing members formed integral therewith, the front wall of the body section having, at its upper edge, an integral reinforcing member, said member, in combination with the upper reinforcing members of the end wall sections, forming a support for the top or cover part of the resulting chest, the corner posts extending below the bottom wall of the assembled chest, said bottom wall having end extensions seating upon the inwardly extending bottom reinforcements of said end walls, the corner posts of the end wall sections having the wall parts therewith secured to said posts, the posts having grooves receiving end edges of the front and back walls of the chest, and fastener devices for securing the front and back walls to said posts.

3. A knockdown chest comprising a body section and two similar end wall sections, said body section comprising foldably related front, back, bottom and top wall parts, said end sections each comprising a pair of corner posts joined and spaced solely by a wall portion, said wall portion having, at upper and lower ends thereof, inwardly extending reinforcing members formed integral therewith, the front wall of the body section having, at its upper edge, an integral reinforcing member, said member, in combination with the upper reinforcing members of the end wall sections, forming a support for the top or cover part of the resulting chest, the corner posts extending below the bottom wall of the assembled chest, said bottom wall having end extensions seating upon the inwardly extending bottom reinforcements of said end walls, the corner posts of the end wall sections having the wall parts therewith secured to said posts, the posts having grooves receiving end edges of the front and back walls of the chest, fastener devices for securing the front and back walls to said posts, and a supplemental top wall part secured to and reinforcing the top wall and forming a four ply thickness throughout the major portion of said top wall.

4. A knockdown chest comprising a body section and two similar end wall sections, said body section comprising foldably related front, back, bottom and top wall parts, said end sections each comprising a pair of corner posts joined and spaced solely by a wall portion, said wall portion having, at upper and lower ends thereof, inwardly extending reinforcing members formed integral therewith, the front wall of the body section having, at its upper edge, an integral reinforcing member, said member, in combination with the upper reinforcing members of the end wall sections, forming a support for the top or cover part of the resulting chest, the corner posts extending below the bottom wall of the assembled chest, said bottom wall having end extensions seating upon the inwardly extending bottom reinforcements of said end walls, the corner posts of the end wall sections having the wall parts therewith secured to said posts, the posts having grooves receiving end edges of the front and back walls of the chest, fastener devices for securing the front and back walls to said posts, a supplemental top wall part secured to and reinforcing the top wall and forming a four ply thickness throughout the major portion of said top wall, and the reinforcing members

at upper ends of the front and end walls having parts seating upon the upper ends of the corner posts.

5. In a knockdown chest comprising a body section and end sections detachable with respect to the body section, said body section comprising front, back and bottom walls and a hinge cover wall, each end section comprising corner posts joined and spaced by a wall portion, the lower end of the wall portion having inwardly, downwardly and upwardly arranged integral parts forming an inwardly directed shoulder upon the inner surface of the end wall part intermediate the corner posts, and the shoulders of the end wall sections forming supports for the ends of the bottom wall of the body section supporting said wall above the lower ends of said corner posts.

6. In a knockdown chest comprising a body section and end sections detachable with respect to the body section, said body section comprising front, back and bottom walls and a hinge cover wall, each end section comprising corner posts joined and spaced by a wall portion, the lower end of the wall portion having inwardly, downwardly and upwardly arranged integral parts forming an inwardly directed shoulder upon the inner surface of the end wall part intermediate the corner posts, the shoulders of the end wall sections forming supports for the ends of the bottom wall of the body section supporting said wall above the lower ends of said corner posts, and said end wall sections having integral substantially triangularly-shaped reinforcing members extending the full length of the upper edges thereof intermediate the corner posts.

7. In a knockdown chest comprising a body section and end sections detachable with respect to the body section, said body section comprising front, back and bottom walls and a hinge cover wall, each end section comprising corner posts joined and spaced by a wall portion, the lower end of the wall portion having inwardly, downwardly and upwardly arranged integral parts forming an inwardly directed shoulder upon the inner surface of the end wall part intermediate the corner posts, the shoulders of the end wall sections forming supports for the ends of the bottom wall of the body section supporting said wall above the lower ends of said corner posts, said end wall sections having integral substantially triangularly-shaped reinforcing members extending the full length of the upper edges thereof intermediate the corner posts, and said members including parts extending onto upper edges of the posts.

8. In a knockdown chest comprising a body section and end sections detachable with respect to the body section, said body section comprising front, back and bottom walls and a hinge cover wall, each end section comprising corner posts joined and spaced by a wall portion, the lower end of the wall portion having inwardly, downwardly and upwardly arranged integral parts forming an inwardly directed shoulder upon the inner surface of the end wall part intermediate the corner posts, the shoulders of the end wall sections forming supports for the ends of the bottom wall of the body section supporting said wall above the lower ends of said corner posts, said end wall sections having integral substantially triangularly-shaped reinforcing members extending the full length of the upper edges thereof intermediate the corner posts, said mem-

bers including parts extending onto upper edges of the posts, and the front wall of the chest having a corresponding reinforcing member at the upper edge thereof intermediate posts of said end wall sections.

9. A chest of the class described comprising front, bottom, back and end walls and a top hinged cover wall, corner posts at the four corners of the chest, said posts having grooves to receive the edges of the front, back and end walls in joining said walls, said posts being of a height greater than the depth of the front and back walls of the chest, the end walls having inwardly set integral reinforcing portions throughout the length of the lower ends thereof extending said walls to a depth corresponding to that of said posts, and said inwardly set reinforcing portions forming supports for the bottom wall of the chest.

10. In knockdown chests composed of sheet material, said chest having integral foldably related front, back and bottom walls and detachable end walls, corner posts reinforcing and joining front and back walls with said end walls, said posts extending to form leg members for the chest, means formed integral with upper edge portions of the front and end walls to widen and reinforce said edges, said means comprising substantially tri-angular portions of the material of said walls, each tri-angular portions comprising

5 ing a part extending inwardly at right angles to the upper end of the wall, a part extending downwardly and outwardly at an angle to said wall, a part extending upwardly on the inner surface 10 of said wall, means integral with the end walls for reinforcing lower portions thereof, said last named means comprising an inwardly extending part and downwardly and upwardly extending parts arranged one upon the other and set inwardly with respect to said end walls, and said last named means forming supports for end portions of the bottom wall of the chest at a point raised with respect to the lower ends of said leg members.

15
